UNITED STATES PATENT OFFICE.

CLARENCE P. BYRNES, OF SEWICKLEY, PENNSYLVANIA.

METHOD OF AND APPARATUS FOR DRAWING GLASS.

1,425,746.

Specification of Letters Patent. Patented Aug. 15, 1922.

Application filed January 28, 1918. Serial No. 214,065.

To all whom it may concern:

Be it known that I, CLARENCE P. BYRNES, a resident of Sewickley, in the county of Allegheny and State of Pennsylvania, have 5 invented a new and useful Improvement in Methods of and Apparatus for Drawing Glass, of which the following is a full, clear, and exact description, reference being had to the accompanying drawings, forming part 10 of this specification, in which:

Figure 1 is a diagrammatic sectional side elevation showing one form of apparatus for carrying out my invention;

Figure 2 is a general plan view of the 15 drawing apparatus showing the gearing, chains, etc.;

Figure 3 is a detail side elevation partly broken away of one of the deforming lifters;

Figure 4 is a partial front elevation showing a pair of the chains with one of the de- 20 forming lifters;

Figure 5 is a detail view of a guide for the lifter;

Figure 6 is a diagrammatic sectional side 25 elevation showing the crack-off apparatus and lifter and carrier for the cracked-off sections; and

Figure 7 is a partial sectional side elevation showing one means for starting the 30 draw.

My invention relates to the drawing of glass cylinders from a bath of molten glass, and particularly to the drawing of a continuous cylinder, the upper portions of which 35 are successively cut off and removed during the drawing operation.

Heretofore, the continuous drawing of cylinders has proven impracticable partly because the roller grippers designed to 40 engage and lift the cylinder did not possess sufficient friction to lift it properly. If made of wood or similar material, they char, and if made of metal or similar material, they crack and break the cylinder.

My invention overcomes this difficulty by 45 providing traveling lifters which move with the cylinder and are preferably arranged to engage portions of it which are deformed in the plastic zone either by the lifters or by 50 special additional deforming devices.

In the lower part or plastic zone of a rising cylinder within a zone near the level of the glass bath, the glass may be indented, 55 perforated or deformed locally; and by en- gaging such deformed portions, I provide

for lifting a continuous cylinder. The deformed portions are preferably localized around the circumference of the cylinder and are preferably spaced apart a suitable distance to provide ordinary "roller" lengths 60 between them, the sections being preferably cut off at or adjacent to its deformed portions. The deforming means is preferably driven into the glass with considerable rapidity to make a local tear without bending 65 the adjacent wall inwardly, which occurs if the pressure is applied slowly; although some bending in around the deformed portion will be straightened out by the pull of the portions of the cylinder above as it rises. 70

The invention also relates to the continuous drawing of a cylinder from a "forehearth" portion of a tank furnace; to properly supplying the distending air and holding the desired pressure within the plastic 75 zone; to improved traveling crack-off apparatus; and to the engaging and carrying away of the upper cut sections. It also relates to a shield which may preferably be used to protect the machinery and to other 80 parts and combinations more fully herein-after described and claimed.

In the drawings, 2 represents a tank furnace having a forehearth portion 3, the floor 4 of which is preferably above the level 85 of the glass in the tank, although this may be varied; and if a series of forehearts are used along the side or end of the tank, the bottoms of the forehearts may be varied in height to suit the conditions. 90 is a pier which supports a portion of the topstone 6 and the shade or shield 7. A refractory nozzle 8 projects up through the forehearth to a point above the level of the glass therein and is supplied with air from a 95 suitable supply pipe 9. Through the supply pipe projects a vertically movable tube or rod 10, carrying at its upper end a refractory disk baffle 11, which is of circular shape and which may be adjusted vertically 100 to any desired position. This baffle is designed to hold the air pressure within the plastic zone and to give the proper distending action in the cylinder.

The numeral 12 designates a floating refractory ring surrounding the air supply nozzle and spaced apart from it, this ring being preferably held in position by a water-chilling ring 13, supported by any suitable suspending means and preferably vertically 110

adjustable. Water is circulated through this ring during the drawing operation. 14 represents a burner which may be used to keep the outer portion of the glass in the forehearth at or near the temperature of that portion of the bath close to the body of glass in the tank, the forehearth being preferably arranged to keep the glass of substantially the same temperature in the various portions thereof around the draw. The continuous glass cylinder 15 is drawn up from the bath around the baffle through the water-cooling ring. After the cylinder has been drawn up a certain distance by a circular bait, which may be raised vertically in any desired manner, the cylinder is engaged in the plastic zone by a set of deforming lifters 16, one of which is shown in detail in Fig. 3. As herein shown, it consists of a swinging hanger provided with a rear cam projection 17, and with a forwardly projecting deformor 18. This deformor may be formed of copper or any desirable metal or alloy, and is preferably hollow, and may be provided with an asbestos covering 19 in its engaging portion.

The set of deforming lifters is preferably spaced equidistant around the cylinder, there being four of these lifters in the form shown, 30 each lifter being pivoted on a cross bar 20, extending between the two sprocket chains 21. There is a series of the sets of lifters mounted on the pairs of chains, the sets being spaced apart any desirable distance, 35 preferably a distance equal to the length of the sections desired, or substantially so.

The chains are shown as being carried over sprocket wheels 22, 23 and 24, the wheels 22 being placed vertically over the 40 wheels 24. The set of sprocket wheels for each line of lifters is preferably mounted on a framework indicated at 25, hung on overhead wheels 26 and 27, mounted in horizontal channels or guides underneath the floor 45 28 of the upper or crack-off and removing station. Each set of chains may be adjusted back and forth by set screws 29, and the chains may be driven through the shafts 30, of the sprocket wheels 23, these shafts connecting at their ends through bevel gears 31. 50 32 represents an electric motor having a worm gear connection 33, with one of the shafts 30.

To force the deforming lifters into the 55 wall of the cylinder, I preferably provide vertically extending cam guides or tracks 34, having rearwardly curved upper and lower end portions, these guides being preferably adjustable toward and from the cylinder, as indicated at 35. 36 and 37 represent guides for the hangers to control their movement, as they pass down toward the cylinder, these guides being preferably slotted, as shown at 38 in Figure 5, to allow passage of the de- 60 forming projections.

As the deforming lifters leave the lower ends of the guides 36 and 37, the cam projection 17 will be engaged by the cam tracks, and as these projections are near the pivot points, the deformers will be rapidly forced forward into the cylinder in the plastic zone, forming the inwardly projecting teats. As the lower set of lifters moves up at the speed of and with the cylinder, the cylinder is being lifted by the upper sets of 75 lifters which are engaging the set and colder portions of the cylinder.

I have shown four sets of deforming lifters engaging the cylinder, before it reaches the floor of the upper station, and as the upper lifters reach the sprocket wheels 23, they are released by the cam guides and swing back out of the deforming portion of the cylinder, there always being at least two sets to perform the lifting operation by engaging 85 the upper side portions of the cylinder after the plastic zone is passed.

As the cylinder rises through the hole in the floor 28, it is cracked off in sections, preferably at or adjacent to the deformed portions, preferably by a heated electric wire which is now well known in this art. The electric wire loop preferably extends between side holders 39 and 40, which are arranged to slide vertically on guides 41, the 95 loop or circle remaining normally opened. Handles 42 are provided for clamping the electric wire around the glass cylinder, preferably just above a set of indentations or deformations, as shown in Figure 6. This 100 is done while this portion of the cylinder is near the floor. When the operator thus clamps the wire around the cylinder, the electric current is turned on to heat the wire, which rises with the cylinder, thus giving a 105 traveling crack-off. The operator after heating the circumference of the cylinder preferably applies a cold iron or otherwise finishes the crack-off operation and releases the handles 42, whereupon the crack-off apparatus drops down to its original position 110 ready for the next section. I also preferably utilize the deformed portions of the cylinder for engaging the cylinder sections to remove them after cracking off.

Thus, in Figure 6, I show a glass-section-engaging device comprising a central portion 43, provided with radially swinging arms 44, which may be widened at their ends or provided with arc-shaped sections, 120 this device being supported from a flexible cable 45, extending over the guide wheels 46 and 47 of a trolley 48 and down to a counterweight 49. The cable is preferably provided with a stop device 50, arranged 125 to engage a spring 51 to form a stop and cushion the checking of the lifting action of the sections when severed.

As the continuous cylinder rises, the lifter device is lowered into it by the operator, 130

the arms are extended under the teats and the counterweight then allowed to act, this giving an upward tension on the upper uncut sections. The crack-off device is then 5 operated at the proper time to cut the lower end of this section, whereupon the weight will lift the section away from the rising cylinder, and the trolley may then move off on its track 52 and the section lowered and 10 laid on a horse for cracking off the indenting portion and splitting lengthwise.

While the original bait used for starting the continuous cylinder may be lowered into the bath and raised by separate mechanism 15 of any desirable form, I may employ the mechanism shown for this operation. This may be done by providing a metal bait 53, shown in Figure 7, having an upper rim portion which may be raised on the projecting deformers on the lifters. By clipping back a series of lifters in place, the movement of the chains may be reversed, and the bait, which has been applied at an upper point, can be lowered down until its 20 lower edge portion is in the bath, as shown in Figure 7. The chains may then start in their normal movement to lift the bait, and the lifters then unclipped and unfastened and allowed to go through their normal 25 operation.

The speed of the chains may, of course, be varied by suitable control of the electric motor or drive, and in the starting of a draw will preferably be gradually increased 30 until an equilibrium is established between the speed of draw and the action of the heating and cooling of the bath to give a cylinder of substantially uniform thickness. After this equilibrium is established, the 35 chains may be driven at a uniform speed, giving a cylinder of uniform thickness thereafter, so long as the heating and cooling conditions are maintained substantially uniform.

40 The refractory floating ring and the water chill may be shifted sidewise as desired, and when shifted, the deformers may indent or deform more on one side than the other, so long as they properly deform the glass so 45 as to engage and lift it.

In Figure 2, I have shown a cylindrical shield 54, provided with vertical slots to allow passage of the deformers, this shield preferably being made of sheet material, 55 such as asbestos, sheet steel, etc. It may extend for any desired portion of the length of the draw, and will act to protect the chain mechanism from the heat. It may be used or not as desired.

60 The advantages of my invention result mainly from the new principle of lifting the cylinder by traveling grippers which engage it, preferably by coacting with the deformed portions thereof. An efficient and 65 reliable means is thus provided for lifting

the cylinder and the speed of draw may be maintained or changed as desired, owing to the positive engagement of the grippers with the cylinder. The deforming also aids in providing for engagement and removal 70 of the upper sections as cracked off, and there is little loss of marketable glass as the indented portions are localized and may be at the points of cracking off or severing the lengths. For this reason, the crack-off is 75 preferably just above the set of indentations. The tension applied to the upper section before severing insures quick removal from the upwardly moving cylinder and avoids breakage. The supply of air up 80 through the nozzle in the bath along with the baffle provides for the distension of the cylinder, without interfering with the continuous draw. The traveling crack-off device allows the continuous movement of the 85 cylinder, which is important, as stoppage will interfere with the operation and change the thickness of the glass.

The stem of the baffle may be water-cooled, if desired, although the flow of air 90 around it will usually cool it sufficiently. The deformations may be made by mechanism separate from the chains and acting in place of the grippers on the chains, which latter will engage the indentations made by 95 the separate indentation-forming mechanism.

The mechanism for moving the deformers may be varied, the deformers may be directly attached to the chains, other means 100 may be used for driving the deformers into the glass in the plastic zone, and many other changes may be made without departing from my invention.

I claim:

1. In the drawing of hollow glass articles, the steps consisting of continuously drawing a hollow glass article upwardly from a molten glass bath, locally deforming portions of the cylinder during the 110 drawing operation, and lifting the cylinder by engagement with said deformed portions during the continuous draw.

2. In the drawing of hollow glass articles, the steps consisting of continuously 115 drawing a hollow glass article upwardly from a bath of molten glass, deforming longitudinally separated portions of the cylinder, and lifting the cylinder by engaging said portions during the continuous 120 draw.

3. In the method of drawing a glass cylinder the steps consisting of deforming a cylinder at separated parts around its circumference and engaging the deformed portions to lift the cylinder. 125

4. In the method of drawing a continuous glass cylinder, the steps consisting of deforming a cylinder at spaced apart portions of its length while the cylinder is being 130

drawn and severing and removing an upper length while continuously drawing a lower length of the cylinder.

5. In the continuous drawing of glass cylinders, the steps consisting of deforming the cylinder at spaced apart portions of its length while the cylinder is being drawn and severing and removing an upper length while continuously drawing a lower length and forming the deformations thereof.

6. In the drawing of hollow glass articles from a tank or forehearth, the steps consisting in feeding air upwardly through the bath, baffling the air to retain distending pressure for the hollow glass body while allowing baffled air to pass upwardly through the hollow body, and drawing the glass body upwardly from within a floating ring by engaging its sides to continuously lift it.

7. In the drawing of glass cylinders from a forehearth or tank, the steps consisting of feeding air upwardly through the bath, baffling the air to retain the distending pressure within the cylinder, while allowing the baffled air to pass upwardly through the cylinder, drawing the cylinder upwardly from within a floating ring and through a chilling device, and engaging the side of the cylinder to lift and draw it.

8. In the drawing of hollow glass articles, the steps consisting of continuously drawing a cylinder, de-forming portions thereof while it is being drawn, and cracking off and removing upper sections thereof on lines at or near the de-formed portions.

9. In the drawing of a continuous cylinder, the steps consisting of deforming portions of the cylinder while it is moving upwardly, lifting the cylinder by engaging said deformed portions, and successively severing the upper sections of the traveling cylinder while continuing the drawing and deforming of lower sections.

10. In the drawing of a continuous cylinder, the steps consisting of deforming portions of the cylinder, lifting the cylinder by engaging said deformed portions, successively severing the upper sections of the traveling cylinder and engaging the deformed portions to remove the severed sections while continuing the drawing and deforming of lower sections.

55 11. In the drawing of a continuous cylinder, the steps consisting of lowering a bait into a bath of molten glass, drawing the cylinder upwardly, deforming separated portions of the cylinder, and thereafter continuously lifting the cylinder thereby while continuously drawing lower portions and de-forming them.

60 12. In the drawing of cylinders from a forehearth or tank, the steps consisting of feeding air upwardly through the bath,

baffling the air to retain a distending pressure within the cylinder, while allowing upward passage of air beyond the baffling point and drawing the cylinder upwardly within a floating ring and through a water chill.

13. In the drawing of continuous glass cylinders, the steps consisting of deforming the cylinder at separated portions of its length and severing sections of the cylinder at or near the deformed portions while continuously drawing lower sections of the cylinder and deforming them.

14. In apparatus for continuously drawing glass cylinders, continuously acting drawing mechanism having means for de-forming the cylinder and lifting the cylinder by engaging the deformed portions during the continuous drawing operation.

15. In apparatus for continuously drawing glass cylinders, endless carriers having means for deforming separated portions of the cylinder and lifting the cylinder by engaging said deformed portions to continuously lift the same.

16. In apparatus for continuously drawing hollow glass bodies upwardly from a molten glass bath, traveling means for indenting and gripping the hollow glass body in separated portions to continuously move it upwardly.

17. In apparatus for drawing glass cylinders, continuously traveling mechanism and means for indenting a cylinder at different parts of its length and continuously lifting it by the indented portions during the continuous draw.

18. In apparatus for drawing glass cylinders, a series of endless carriers having de-forming grippers arranged to deform the wall of the cylinder and lift it upwardly.

19. In apparatus for continuously drawing glass cylinders, automatic means for de-forming the plastic glass within the plastic zone and for gripping the deformed portions to lift the cylinder continuously upwardly and connections for actuating said automatic means.

20. In apparatus for drawing a continuous glass cylinder, traveling means arranged to give a continuous draw said means having mechanism for automatically deforming the cylinder at separated parts of its length during the continuous drawing thereof.

21. In apparatus for drawing hollow glass bodies, de-forming means, and connections for moving the de-forming means to cause the cylinder to move upwardly as it is de-formed.

22. In apparatus for drawing hollow glass bodies upwardly from a bath of molten glass, de-forming means, and an upper section-removing device arranged to engage the deformed portions, the latter device having connections arranged to lift the severed sec-

tion from the upwardly moving hollow glass body.

23. In apparatus for drawing a continuous cylinder, means for indenting and gripping the cylinder and moving it upwardly, and a shield arranged to protect said means.

24. In apparatus for drawing a continuous glass cylinder, a set of traveling mechanisms having means for indenting and gripping the cylinder and continuously moving 15 it upwardly, at least one of said mechanisms being adjustable toward and from the cylinder.

25. In apparatus for drawing a continuous glass cylinder, a set of traveling mechanisms having means for indenting and gripping the cylinder and continuously moving 15 it upwardly, at least one of said mechanisms being adjustable toward and from the cylinder.

In testimony whereof, I have hereunto set my hand.

CLARENCE P. BYRNES.
